Inventor:

Horace Q. Plummer,
By E. S. Silvius.

Attorney.

UNITED STATES PATENT OFFICE.

HORACE Q. PLUMMER, OF DANVILLE, INDIANA, ASSIGNOR, BY DIRECT AND MESNE ASSIGNMENTS, TO THE AMERICAN MANUFACTURING COMPANY AND HENRY T. HEARSEY, OF INDIANAPOLIS, INDIANA.

BICYCLE PEDAL-BELL.

SPECIFICATION forming part of Letters Patent No. 632,471, dated September 5, 1899.

Application filed June 30, 1899. Serial No. 722,371. (No model.)

To all whom it may concern:

Be it known that I, HORACE Q. PLUMMER, a citizen of the United States, residing at Danville, in the county of Hendricks and State of Indiana, have invented certain new and useful Improvements in Bicycle Pedal-Bells; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The invention relates to a bell or gong that is adapted to be applied to and operated in connection with the pedals of bicycles; and it consists in a new and novel frame and operating means therefor whereby the bell may be placed in operative position, means whereby the bell is retained in inoperative position, and in improvements whereby the bell is caused to sound strongly and also with less force alternately; and it consists, further, in the parts and combination and arrangement of parts hereinafter fully described and claimed.

The objects of my invention are, first, to provide a bell which may be sounded when the bicycle is in motion only and without requiring the use of the hands, which are usually otherwise employed; second, to produce such a bell with the least amount of weight in its construction; third, to provide a simple and therefore cheap device of this character, and, fourth, to generally improve the details of construction, so as to be durable and economical in use.

These objects are fully attained in my invention, which is illustrated in the accompanying drawings, in which similar letters and numerals of reference in the several figures designate similar parts.

Referring to the drawings, Figure 1 represents a front elevation of a right-hand-side bicycle-pedal, showing my devices in inoperative position attached thereto; Fig. 2, a central vertical transverse sectional view; Fig. 3, a bottom plan view of the bell-frame in inoperative position; Fig. 4, a bottom plan of the

striker-arm; Fig. 5, a top perspective of the bell-frame, showing the foot-lever when made integrally and non-adjustable with the bell-frame; Fig. 6, a perspective of the striker-arms, and Figs. 7, 8, and 9 detail views.

55

In practically carrying out my invention a metallic base-plate F is provided, which is adapted to fit the pedal-frame A of a bicycle, and it may be of any suitable width. It is preferably designed to bear against the treadle-surface or part against which the foot bears, and secured thereto, as in the present case, by means of a clamp G, extending over the opposite side of the hub B, and screw-bolts H I, extending through perforations s s in the clamp and threaded perforations i i in the base F.

65

A bell-frame D is either made of cast metal or stamped out of sheet metal and is preferably circular, having a flange d adapted to extend over the edge of the bell E as a protection both against injury and against mud and dust. The frame is pivoted at one side to the base by means of a rivet k in a perforation in the frame and a registering perforation l in the base. At the opposite side of the frame and registering with a perforation i is a slot h to receive the extended threaded end of the bolt I, which projects below the frame-plate and is provided with a nut J, which after being 70 adjusted may be suitably locked, but without binding the frame-plate tightly, the frame being permitted to move laterally about its pivot k and being governed in extent of movement by the ends of the slot h acting as stops 75 against the bolt I. The frame has a center stud e, to which the bell is suitably secured, as by a screw f, and at the under side as it hangs below the pedal it has posts 7 and 8 and a split post Q, and near the edge opposite the latter is a perforation n, in which is a pivot m, by which the clapper-lever K, having an axial hole p, is mounted at the under side of the frame. The clapper-lever has a curved inner end terminating in a clapper L of suitable 80

form, and an outer end t, adapted to form contact with the striker-arms O and O', or, if desired, with the arm C of the bicycle-crank. A perforation 6 is adapted to receive the operating-spring. The operating-spring P is 85 90 95 100

formed of wire and is preferably continuous, so that one spring not only retains the bell in its inoperative position, but also acts to throw the clapper against the bell. Thus adapted, 5 it comprises an elliptically-curved main section secured in the split post Q, extending outside the post 7 and inside the post 8 and having its free end hooked in the perforation 10 6 of the lever K or otherwise connected thereto. From the post Q a section 2 extends to and coils about the stud e, as section 4, extending thence, as section 3, the free end of which bears against the side of the lower end of the bolt I immediately below the nut J and 15 may serve as a lock therefor. The tension is such that the post Q is forced normally away from the bolt I, and therefore withdraws the bell-frame and the lever K away from the crank-arm C and the end t from contact with 20 the striking means. The post 7 allows great elasticity when the lever K is in contact with the striking means, and the post 8 causes a rebound after the clapper strikes the bell. The striker-arms have a hub in which is an 25 aperture y to receive the end b of the axle of the pedal, and is secured between the boss C' and the shoulder a. One or more arms O may be employed, and when more than one there is preferably one or more arms O' set over, so 30 that the end t barely forms a contact, so that a subdued sound of the bell is produced, alternating with the loudest sound produced by contact with the arm O. Thus the monotonous tones of other bells are obviated, and a warning of greater effect is given. This effect is attained by reason of the positive frame-stops 35 and the offset-arms, as the straight arms O, which, however, may be offset in the opposite direction to the others, cause the lever end t 40 to have a greater travel than do the others, as will be obvious.

In order to render the device operative, I provide an arm whereby the bell and its frame and operating elements are brought by the 45 foot of the rider into operative contact with the motive force. This arm is rigidly attached to the frame D and may be either formed separately, as N, having a slot u, whereby it is adjustable, and a screw-bolt v, securing the 50 same to a lug M of the frame and against a shoulder w, or as an integral arm M', extending upward from the frame above the pedal-frame, so that it may be engaged by the rider's shoe-sole or the foot. In low-gear bicycles it 55 may be desirable to dispense with the striking-arms, as the lever K is equally adapted to act with the crank-arm C, the edge 10 being the contacting side.

In operation, as will be apparent from the 60 foregoing, the rider may press his foot side-wise against the arm N or M' and cause the frame D to swing on its pivot toward the crank-arm C, bringing the elements into operation, as explained in detail, and causing 65 an alarm while so retained by the foot, the alarm ceasing when pressure against the arm is removed. The base is so situate that when

the bell-frame is in the inoperative position the lever K clears the strikers and is normally held, substantially as shown in Fig. 3, by the 70 spring P resting against the post 8.

While the form of spring shown is simple and effective, obviously I may adopt equivalent separate springs without departing from the intent and purpose of my invention, and the arm M' may be bent laterally to any suitable degree to suit a shoe having a broader toe than the arm shown is designed for. 75

Having thus described my invention, what I claim, and desire to secure by Letters Patent, is—

1. A bicycle-pedal provided with a bell-frame pivoted substantially at one of its sides or eccentrically so that its body portion may swing laterally across the pedal and provided 85 with a projecting arm whereby the bell-frame may be shifted laterally, a bell supported by the bell-frame, and a bell-clapper lever pivoted to the bell-frame and projecting toward the bicycle crank-arm. 90

2. A bicycle pedal-bell comprising a base, a bell-frame movably attached to the base and normally retained in inoperative position, a bell, a bell-clapper lever, and an arm attached to the bell-frame whereby the bell-frame may 95 be shifted to bring the bell-clapper lever in operative position in connection with a striker carried by the bicycle crank-arm.

3. A bicycle-pedal provided with a bell-frame pivoted at one side or eccentrically so that its body portion may swing laterally across the bottom of the pedal and provided with an arm projecting above the pedal whereby the bell-frame may be shifted laterally, a bell supported by the bell-frame, a bell-clapper lever pivoted to the bell-frame and projecting toward the bicycle crank-arm, a spring 100 for the bell-clapper lever, and a spring whereby the bell-frame is normally held from swinging 105 toward the bicycle crank-arm. 110

4. A bicycle-pedal provided with a stationary base and a bell-frame pivoted at one side to the base so that the greater portion of the bell-frame may swing laterally toward the bicycle crank-arm, a spring whereby the bell-frame is normally held away from the bicycle 115 crank-arm, an arm whereby the bell-frame may be pressed toward the bicycle crank-arm, a bell, a clapper-lever pivoted to the bell-frame and projecting therefrom toward the 120 bicycle crank-arm, and a spring for the clapper-lever.

5. A bicycle pedal-bell comprising a base and a clamp whereby the same may be secured to the pedal-axle and provided at one 125 end with a pivot-pin, a bell-frame connected to such pivot-pin and working parallel with the base and provided at the side opposite the pivot with a projecting arm adapted to be engaged by the foot of a bicycle rider, a frame-spring, a bell, a bell-clapper lever having a clapper at one end thereof and pivoted to the bell-frame, a bell-clapper spring, and a striking-arm attachable to the bicycle crank-arm. 130

6. In a bicycle pedal-bell, the combination of the pedal, the base, the pivoted bell-frame, the bell, the operating-lever secured to the bell-frame and extending above the pedal 5 whereby the bell-frame is shifted, the clapper-lever having a clapper at its inner end and pivoted to the bell-frame, and the striker-arms secured to the bicycle crank-arm and provided with alternate arms offset away from 10 the clapper-lever whereby the same is engaged by such lever during a lesser period of time than are the remaining striker-arms.
7. In a bicycle pedal-bell, the combination of the pedal, the base F provided with the 15 pivot k and the perforation i, the bell-frame D having the bell secured thereto and the protecting-flange d and slot h and mounted on said pivot, the clamp, the clamp-bolts, the arm attached to the bell-frame, the nut on the 20 clamp-bolt below said slot, the posts, the clapper-lever K pivoted to said bell-frame and projecting therefrom, the striker-arms secured by the pedal-axle, and the spring whereby the bell-frame and the clapper-lever is pressed, 25 substantially as set forth.
8. In a bicycle pedal-bell, the combination of the pedal, the base, the bell-frame, the clapper-lever pivoted to the bell-frame and having a bell-clapper at its inner end and its 30 outer end projecting from the bell-frame, the

striker-arms mounted on the bicycle crank-arm, the spring pressing the bell-frame oppositely from the bicycle crank-arm, the spring tending to hold the clapper elastically near the bell, and an arm attached to the bell-frame 35 whereby the same may be shifted about its pivot so that said clapper-lever may form contact with the striker-arms, substantially as set forth.

9. In a bicycle pedal-bell, the combination 40 of the pedal, the bicycle crank-arm, the base, the bell-frame, the stops for the bell-frame, the clapper-lever pivoted to the bell-frame and projecting toward such crank-arm, the operating-arm attached to the bell-frame, the 45 frame-spring, the clapper-lever spring, and the striker-arms carried by such crank-arm and situate in different planes whereby such clapper-lever is engaged and moved a greater distance about its pivot by the striker-arms 50 nearest thereto than by such striker-arms in the plane farthest therefrom, substantially as and for the purposes set forth.

In testimony whereof I affix my signature in presence of two witnesses.

HORACE Q. PLUMMER.
